US00D892774S

(12) **United States Design Patent** (10) Patent No.: **US D892,774 S**
(45) Date of Patent: **** Aug. 11, 2020**

(54) **WIRELESS TRANSMISSION/RECEPTION MODULE**

(71) Applicant: **Murata Manufacturing Co., Ltd.**, Nagaokakyo-shi, Kyoto-fu (JP)

(72) Inventors: **Kaoru Sudo**, Nagaokakyo (JP); **Michiharu Yokoyama**, Nagaokakyo (JP); **Hideki Ueda**, Nagaokakyo (JP); **Ryuken Mizunuma**, Nagaokakyo (JP); **Masayuki Nakajima**, Nagaokakyo (JP)

(73) Assignee: **MURATA MANUFACTURING CO., LTD.**, Nagaokakyo-Shi, Kyoto-Fu (JP)

(**) Term: **15 Years**

(21) Appl. No.: **29/645,309**

(22) Filed: **Apr. 25, 2018**

Related U.S. Application Data

(60) Continuation-in-part of application No. 29/555,860, filed on Feb. 25, 2016, now Pat. No. Des. 830,348, which is a division of application No. 29/485,828, filed on Mar. 24, 2014, now Pat. No. Des. 757,693.

(57) **CLAIM**

The ornamental design for a wireless transmission/reception module, as shown and described.

DESCRIPTION

FIG. 1 is a front view of a wireless transmission/reception module of a first embodiment showing our new design;

FIG. 2 is a top plan view thereof;

FIG. 3 is a bottom plan view thereof;

FIG. 4 is a left side view thereof;

FIG. 5 is a perspective view 1 thereof;

FIG. 6 is a perspective view 2 thereof;

FIG. 7 is a front view of a wireless transmission/reception module of a second embodiment showing our new design;

FIG. 8 is a top plan view thereof;

FIG. 9 is a bottom plan view thereof;

FIG. 10 is a left side view thereof;

FIG. 11 is a perspective view 1 thereof;

FIG. 12 is a perspective view 2 thereof;

FIG. 13 is a front view of a wireless transmission/reception module of a third embodiment showing our new design;

FIG. 14 is a top plan view thereof;

FIG. 15 is a bottom plan view thereof;

FIG. 16 is a left side view thereof;

FIG. 17 is a perspective view 1 thereof; and,

FIG. 18 is a perspective view 2 thereof.
